UNITED STATES PATENT OFFICE.

ALPHONZO HAVEN, OF BROCKTON, MASSACHUSETTS.

BOOT OR SHOE.

SPECIFICATION forming part of Letters Patent No. 366,095, dated July 5, 1887.

Application filed December 13, 1886. Serial No. 231,444. (No model.)

To all whom it may concern:

Be it known that I, ALPHONZO HAVEN, of Brockton, in the county of Plymouth and State of Massachusetts, have invented certain new and useful Improvements in Boots or Shoes, of which the following is a specification.

My invention relates to boots or shoes of the kind commonly known as "Congress," having an elastic gore at the sides of the ankle portion, the function of which elastic gore is to provide for a yielding of that portion of the boot or shoe in which it is set, so that it can be readily drawn on or off the foot of the wearer, and to cause the top or leg portion of the shoe to neatly fit or closely hug the ankle when said shoe is in position on the foot.

It is the object of my invention to provide improved means whereby such elastic gore may be adjusted to suit any peculiar form or size of ankle where the shoe is otherwise smoothly and properly shaped to fit the foot, so as not only to secure comfort to the wearer, but avoid the expense attending the necessity of having shoes especially made in order to merely suit such peculiar size or form of ankle.

My invention consists in the construction hereinafter described and set forth.

Reference is to be had to the accompanying drawings, and to the letters of reference marked thereon, similar letters indicating similar parts in all of the views.

Of the drawings, Figure 1 represents a side view of a Congress shoe embodying my invention, showing the two parts of the goring closely and fully laced. Fig. 2 represents a like view, showing the lace-string partially removed. Fig. 3 represents a section on the line xx , Fig. 2.

In carrying out my invention I construct a Congress boot or shoe, a , in any suitable or known manner, except as to the elastic goring at the sides of the ankle, and this goring I make in two parts or sections, $b c$, instead of one, as heretofore—that is, I make the goring as though the form heretofore common were longitudinally divided in the center, and stitch to the edges formed by this division

a binding, d , in which at proper intervals I 5c secure eyelets e , and draw said edges together, or as nearly together as may be desired, by a lace-string, f , "threaded" back and forth through the eyelets, in the usual manner of lacing a shoe, the sections $b c$ extending to the 55 extreme top of the ankle portion, so that the usual elasticity of the ankle portion is preserved. I also prefer to stitch to one of the parts—in this instance shown as the part c —one edge of a tongue, g , of leather, and adapted 60 to perform the functions usually fulfilled by such articles in lace-shoes.

By the means described an elastic goring of a Congress shoe can be adjusted to suit the size or form of the foot or ankle of the wearer, 65 or so as to secure the greatest ease and comfort, and when so adjusted the ends of the lace-string can be securely tied and the adjustment maintained, the shoe being used without unlacing, in the same manner as an ordinary Congress shoe, in drawing it on or removing it from the foot.

I am aware that lace-shoes have heretofore been constructed in which strips of elastic material have been inserted and sewed into holes 75 cut in the leather for that purpose on each side of the shoe over and above the instep, such elastic strips being laced tightly together, but not extending to the top of the ankle portion. While this construction fairly meets its 80 purpose of providing for a free and easy use of the ankle-joint under ordinary circumstances, it does not enable the shoe to be applied and removed without unlacing it. My invention is not a lace-shoe, and the lacing-cord f is not loosened preparatory to applying and removing the boot.

I am also aware that it has been proposed to construct a Congress boot with compound gores—that is, with elastic gores having a non- 90 elastic strip down the center; but in constructions of this character there is no adjustment of the gores to fit ankles of unusual size or shape, as in my shoe.

Having thus described my invention, what 95 I claim is—

A Congress gaiter having two elastic side gores, one of which is divided into sections

b c, extending to the extreme top of the ankle portion, and having eyeleted bindings *d d* at their adjacent edges, a lacing, *f*, whereby said sections may be permanently secured at any 5 desired adjustment, and a tongue, *g*, secured to the inner edge portion of one of said gore sections, substantially as set forth.

In testimony whereof I have signed my name

to this specification, in the presence of two subscribing witnesses, this 8th day of December, 1886.

ALPHONZO HAVEN.
